UNITED STATES PATENT OFFICE.

JAMES R. CRACROFT, OF EMPORIA, KANSAS.

HARNESS ATTACHMENT.

Application filed March 23, 1926. Serial No. 96 810

The present invention relates to improvements in harness attachments and has particular reference to a breeching strap connecting member.

- 5 An important object of the invention is the provision of a simple and durable connecting member adapted to permit convenient attachment of the breeching stays to the engaging loops of the breeching.
- 10 A further object of the invention is the provision of breeching connecting means designed to permit convenient adjustment of the breeching or hip straps.

Still another object of the invention is the provision of a member which will greatly facilitate the connection of the hip straps to the breeching loops and which will permit rapid adjustment of the breeching at all times.

A still further object of the invention is the provision of a harness attachment of the above character which will provide a strong and durable connecting means and which can be manufactured at a comparatively low cost.

Other objects and advantages of the invention 25 will become apparent as the description progresses.

In the accompanying drawing forming a part of this specification and in which like reference characters are employed to designate corresponding parts throughout the same:

Figure 1 is a side elevational view of a harness breeching shown in operative position upon a draft animal.

35 Figure 2 is an enlarged sectional view taken on the line 2—2 of Figure 1, and

Figure 3 is a perspective view of the connecting member comprising my invention.

With reference to the drawing, wherein for 40 the purpose of illustration is shown the preferred embodiment of my invention, the numeral 10 generally designates a conventional form of breeching strap which extends about the hind quarters of the draft animal and is provided at its forward ends with circular breeching loops 11. The intermediate portions of the breeching strap 10 usually carry a second pair of breeching loops of rectangular formation as indicated at 12. The forward loops 11 are mounted in a pivoted manner in the extremities of the breeching straps and project forwardly for connection with hold back straps 13 which are connected with the forward portion of the vehicle thills. 45 50 55

the back of the animal forming what are commonly termed breeching stays or hip straps 14. Ordinarily two of these straps are arranged to connect with the forward and rear breeching loops 11 and 12 adapted to conveniently support the breeching on the animal.

It is customary at the present time to connect the breeching stays 14 with the breeching loops by passing the end portions of the stays through the loops and connecting the same by means of a comparatively large buckle, having a pivoted tongue engageable with apertures formed in the stays. While 70 these buckles are very commonly used, they are extremely impractical as the pivoted tongues carried thereby become immovably wedged on the transverse supporting bars due to corrosion of the buckle member. It has also 75 been noted, that the buckle tongues become tightly wedged in the openings of the stays so that it is very difficult to disengage the ends of the stays for re-adjustment of the breeching. With this in mind, my invention 80 contemplates the provision of a novel fastening member adapted to provide a more rapid means of connecting the stays with the breeching loops and capable of much more convenient re-adjustment of the stays relative to 85 the fastening members so as to elevate or lower the breeching on the animal.

Referring now with particularity to the structure of my improved fastening member, the numeral 15 generally designates the body 90 plate which is of durable metallic construction and tapered formation, tapering from a comparatively wide upper end portion to a substantially decreased rounded lower end portion. The lower tapered end of the body 95 plate 15 is turned upwardly and forwardly of the plate to form a substantially U-shaped loop engaging lip 16. Firmly secured to the intermediate portion of the body plate 15 on its vertical center line and projecting transversely from the outer face thereof is a stay engaging pin 17 adapted to readily engage suitable apertures 18 formed in the breeching stays. In order that the end portions of the stays or hip straps 14 may be 100 securely held in longitudinal position on the connecting member the upper and lower portions of the body plate 15 carry longitudinally aligned brackets 19 and 20. These brackets are of U-shaped formation and preferably 105 formed integral with the body plate, the structure being formed by casting or in any 110

suitable manner. It will be noted, from Figures 2 and 3 of the drawing, that the lower bracket 20 is of substantially greater depth than the upper bracket, the purpose of which 5 will become apparent as the description progresses. The brackets 19 and 20 are arranged on the longitudinal center of the plate above and below the stay engaging pin 17 and are arranged to easily receive the hip straps 10 therethrough so as to retain the connecting portions of the straps snugly against the outer face of the body plate.

As can be readily determined from the foregoing description and the drawing, the 15 connecting portions of the breeching stays may be readily secured to the connecting members by inserting one end of the stay through the upper bracket 19 and inserting the pin 17 in the desired aperture of the 20 stay. The extreme end portion of the stay is then inserted through the lower bracket 20 so that the portions of the stay adjacent the pin connection are restrained from lateral movement by the brackets and thus prevent 25 disconnection of the stays from the pins. When the adjustment of the breeching straps necessitates the projection of a substantial length of the end portions of the stays, the extension may be bent backward in doubled 30 formation and returned through the lower bracket 20 so as to snugly retain the end portions of the stays in compact formation.

It can be therefore readily seen that a fastening member for breeching stays of a

very durable and compact construction has 35 been devised, particularly designed with a view of producing a device which will permit convenient adjustment of the hip straps at all times. This device has been produced to obviate the difficulty experienced in the 40 adjustment of the fastening devices employed for this purpose at the present time so that the breeching straps may be readily adjusted, to conform to the animal, with ease and facility.

It is to be understood that the form of my invention herewith shown and described is 45 to be taken as the preferred example of the same and that various changes as to the shape and size may be resorted to without departing 50 from the spirit of the invention or the scope of the subjoined claim.

Having thus described my invention, I claim:

A device of the kind described comprising 55 an elongated plate having one end turned back to form a U-shaped loop extending from the plate adjacent its other end and having a height such as to closely engage a harness strap, a second U-shaped loop adjacent the 60 hook and also projecting from the plate, said second loop being higher than the first loop to loosely engage said harness strap, and a pin projecting from the plate intermediate the loops to engage a hole in said strap. 65

In testimony whereof I affix my signature.

JAMES R. CRACROFT.
